CLAIM

The ornamental design for a paint edger with horizontal and vertical guide wheels, as shown and described.

DESCRIPTION

FIG. 1 is a perspective view of a paint edger with horizontal and vertical guide wheels showing our new design with the broken lines showing an extension pole, removable applicator, and adjacent wall and ceiling structure being for illustrative purposes only and forming no part of the claimed design;

FIG. 2 is a left side elevational view of the edger of FIG. 1 shown with the handle in an alternate position;

FIG. 3 is a right end elevational view of FIG. 2;

FIG. 4 is a right end elevational view of FIG. 2;

FIG. 5 is a right side elevational view of FIG. 2;

FIG. 6 is a top plan view of FIG. 2; and,

FIG. 7 is a bottom plan view of FIG. 2.
